UNITED STATES PATENT OFFICE

FRANK GILLETTE, OF GENOA, AND CHESTER R. PIEPER, OF LA CROSSE, WISCONSIN

SIGNAL

Application filed August 22, 1929. Serial No. 387,723.

This invention aims to provide a simple means whereby a signal will be sounded in the event of conflagration, the structure being capable of being mounted on the ceiling of a basement, in chimneys, or any other place where a fire is likely to start unobserved.

It is within the province of the disclosure to improve generally and to enhance the utility of devices of that sort to which the present invention appertains.

With the above and other objects in view, which will appear as the description proceeds, the invention resides in the combination and arrangement of parts and in the details of construction hereinafter described and claimed, it being understood that changes may be made in the precise embodiment of the invention herein disclosed, within the scope of what is claimed, without departing from the spirit of the invention.

In the accompanying drawings:

Figure 1 shows in elevation, a system constructed in accordance with the invention; and

Figure 2 is a similar view showing a modification.

In carrying out the invention, as shown in Figure 1, there is provided a pair of guides 1 in which slides an operating member 2. The operating member 2 is depressed by a compression spring disposed about a portion of the operating member, one end of the spring engaging one of the guides 1, and the opposite end of the spring engaging an abutment 4 on the operating member 2, the abutment being a washer and pin, if desired.

The numeral 5 designates a pair of guides in which a slide 6 is mounted for reciprocation, the slide 6 preferably being a rigid arm provided at one end with a rectangularly disposed support 7 engaged beneath the reduced lower end 8 of the operating member 2, to hold the operating member against the thrust of the spring 3.

The numeral 9 marks a compression spring disposed about a portion of the slide 6. One end of the spring 9 abuts against one of the guides 5, and the other end of the spring engages an abutment 10 on the slide 6. The abutment 10 may consist of a pin and washer.

The numeral 11 marks any accessible part of a building, carrying an anchor 12, such as a screw eye.

A connection extends between the anchor 12 and the slide 6, and is denoted generally by the numeral 14. The connection may be made in various ways, but as shown, it comprises links 15 provided with rings 16 at their ends, fusible wires 17 being connected between the rings 16, and between one of the rings 16 and the anchor 12. The connection 14, of course, may be of any desired length: its function is to hold the slide 6 drawn to the left, as shown in Figure 1, the spring 9 being under compression, and the support 7 of the slide 6 being disposed beneath the end 8 of the operating member 2, to hold the operating member against movement responsive to the spring 3.

The numeral 18 marks a lever which is fulcrumed intermediate its ends, as at 19. A flexible connection 20 unites one end of the lever 18 with one end of the operating member 2. The lever 18 constitutes a stopping dog, cooperating with the teeth 21 of a wheel 22 to hold the wheel against rotation, the wheel being journaled on the fixed stub shaft 23. The wheel 22 is rotated through the instrumentality of a torsion spring 24, one end of the spring being connected to the stub shaft 23 and the other end to the wheel 22. The wheel 22 constitutes part of a signal. The signal includes a striker 25 fulcrumed at 26 intermediate its ends, one end of the striker cooperating with the teeth 21 of the wheel 22, and the opposite end of the striker carrying a hammer 27 adapted to engage a gong 28 or other audible signal.

In the event of fire, one of the fusible wires 17 is melted away, the slide 6 being released, and moving to the right in Figure 1, under the action of the spring 9, the support 7 being moved out of engagement with the end 8 of the operating member 2, the operating member moving downwardly in Figure 1, under the action of the spring 3, the lever or dog 18 being tilted by the action of the connection 20, and being disengaged from the teeth 21 of the wheel 22. The wheel 22 then rotates under the action of the spring 100

24, and the teeth 21 cause the striker 25 to swing on its fulcrum 26, the hammer 27 hitting the gong 28, and producing a signal which will be obtrusively audible.

5 In Figure 2, a modification of the invention is shown. In Figure 2, parts hereinbefore described have been designated by numerals previously used, with the suffix "a." The numeral 29 designates an electric bell, or similar audible signal, interposed in a circuit 30 in which is located a source 31 of electrical energy. In the circuit 30 is located a switch mechanism 32, one member 33 of which is held open by the lever 18a.

10 15 When the fusible wire 17 melts, the lever 18a is swung to permit the switch member 33 to close, and then current will flow through the circuit 30 to energize and operate the signal 29.

20 We claim:—

1. A signal-actuating device comprising a lever, means for fulcruming the lever intermediate its ends, an operating member mounted for sliding movement, a connection between the operating member and one end of the lever, means for holding the operating member against movement toward signal-actuating position, a retracting spring cooperating with the last-specified means, and fusible mechanism restraining the last-specified means against movement responsive to the retracting spring.

2. A signal-actuating device comprising two substantially like structures, one of said structures including a slide, and the other of said structures including an operating member, the slide and the operating member having straight-line movement in directions substantially at right angles to each other, spring means for moving the operating member to signal-actuating position, the slide engaging the operating member to hold the operating member against movement responsive to the spring means, spring means for moving the slide out of engagement with the operating member, and fusible means restraining the slide against movement, responsive to the last-specified spring means, to a position out of engagement with the operating member.

3. A signal-actuating device comprising two substantially like structures, one of said structures including a slide, and the other of said structures including an operating member, the slide and the operating member having straight-line movement in directions substantially at right-angles to each other, the operating member being downwardly movable to signal-actuating position, the slide supporting the operating member to hold the operating member against downward movement to signal-actuating position, yieldable means for moving the slide out of supporting relation with respect to the operating member, and fusible means restrain-

ing the slide against movement, responsive to the yieldable means, to a position out of supporting relation to the operating member.

In testimony that we claim the foregoing as our own, we have hereto affixed our signatures.

FRANK GILLETTE.
CHESTER R. PIEPER.
